UNITED STATES PATENT OFFICE.

FREDERICK J. HUBBARD, OF CHICAGO, ILLINOIS, ASSIGNOR TO THE ADAMS & WESTLAKE MANUFACTURING COMPANY, OF SAME PLACE.

VAPOR-STOVE.

SPECIFICATION forming part of Letters Patent No. 387,786, dated August 14, 1883.

Application filed November 9, 1886. Serial No. 218,376. (No model.)

To all whom it may concern:

Be it known that I, FREDERICK J. HUBBARD, of Chicago, in the county of Cook and State of Illinois, have invented certain new and useful Improvements in Vapor-Stoves; and I do hereby declare that the following is a full, clear, and exact description thereof, reference being had to the accompanying drawings, and to the letters of reference marked thereon, which form a part of this specification.

This invention relates to gravity oil-feeding devices of vapor-stoves, and more particularly to those oil-feeding devices in which the oil-supply tank is lowered from its elevated working position to cut off the oil-supply to the burner when the tank is being filled.

The primary object of the invention is to provide a means for cutting off the outward passage for oil from the tank to the burners by the descending movement of the tank or its pipe, so that when the tank is raised after being lowered the oil will not flow to the burners unless the attendant shall first reopen said passage.

Another object of the invention is to provide for the outflow of oil from the burner feed-pipe to the tank when the latter is lowered, while also providing for the closing of the passage by which oil may escape from the tank to the burner feed-pipe when the tank is elevated, as above stated.

To these ends my invention consists in the matters hereinafter set forth, and pointed out in the appended claims.

Referring to the drawings, Figure 1 is a transverse vertical section of a vapor-stove having the well-known "lay-down" tank and provided with my improvements. The pivoted stand-pipe leading downward from the tank is seen upon the end of the stove remote from the eye, and the tank itself is omitted. Fig. 2 is a fragmentary front side view of the part of the stove shown in Fig. 1 and an external view of the parts concerned in my improvements. Fig. 3 is a vertical section of the pipes and connections concerned in my improvement. Fig. 4 is a similar section of a modification.

A represents a vapor-stove top, and A' the uprights of the stove-frame.

B is a horizontal oil-supply pipe running to or beneath the burner or burners.

B' is a branch of the pipe B, leading back to convenient point for the attachment of the pivoted stand-pipe, upon which the oil-supply tank (not shown) is supported.

B² is a branch leading from the rear end of B', parallel with B, and having immediate jointed connection with the stand-pipe.

C is the stand-pipe, pivotally connected with the pipe B² and adapted to be tipped forwardly far enough to bring the tank on the upper end thereof below the level of the burners, which are commonly near the level of the stove-top A.

C' is a guide-bar for the pivoted pipe C.

As heretofore constructed the communication between the pivotal stand-pipe C and the pipe B² has been continually open. In that case the oil flows back from the burners toward the tank when the latter is lowered; but it also flows from the tank to the burners again as soon as the tank is raised. In the construction herein described the passages conveying oil from the tank to the burners is closed upon the descent of the pipe C, and it remains closed after the pipe C is raised. In connection with this construction, provision is also made for the backflow of oil from the burners toward the tank, notwithstanding the closure of the passage for outflow from the tank just referred to.

Referring to Figs. 2 and 3, D is a coupling into which the stand-pipe C is screwed, and which works upon the pipe B² as a horizontal axis. Said pipe B² is preferably reduced at B³, and is provided with a collar or shoulder, D⁴, over which the inner end of the coupling D is constructed to fit, as seen in Fig. 3, and between which collar and the coupling D is inserted a packing, b. The coupling D is forced inwardly toward the collar B⁴ by a suitable nut, B⁵, which confines an interposed packing and washer, B⁶, so that the joint formed by said coupling D with the pipe B² and its extension is tight enough to prevent the escape of oil. The reduced extremity B³ of the pipe B² is drilled inwardly from its end toward the main chamber of said pipe, leaving a diaphragm, through which is provided a passage, b'. The interior of the extension B³ of the pipe B² is provided with an interior

fast thread, in which is fitted a corresponding screw, *e*, upon a stem, *E*. This stem extends outward through a stuffing-box, *E'*, and at its inner end is formed to fit and close the passage *b'*. Leading upwardly from the space occupied by the stem *E* is a passage, *b'*, and through the pipe *B*² and within the coupling *D* is a passage (indicated by dotted line at *b*³, but which is, in fact, on the front side of the pipe) which is cut away instead of through the rear portion of the pipe, which is shown. These two passages may be placed in other positions not in line with each other. From the bottom of the recess *d* in the coupling *D*, *15* into which recess the pipe *C* is secured, are drilled two holes, *d'* *d*², one of which, *d*², is in continuation with the passage *b'* when the pipe *C* is raised, and the other of which, *d'*, is in line with the hole *b*³ when the pipe *C* is lowered. Upon the outer end of the valve-stem *E* is secured a crank arm or lever, *F*, which is directed into position in front of the pipe *C*, as more plainly shown in Fig. 2. In lowering the pipe *C* said pipe therefore strikes the lever *F* and rotates the stem *E*. Said stem, being provided with the fast screw *e*, is turned against its seat in the outer end of the passage *b'* and closes said passage. The lever *F* being entirely unconnected with the pipe *C*, said *25* pipe may be raised into its vertical position without retracting the valve *E*, and the passage *b'* therefore remains closed, and no liquid will flow to the burners from the tank until the lever *F* is thrown and the valve retracted by the attendant.

By the lowering of the pipe *C* the passage *d'*, leading therefrom through the coupling *D*, is, as stated, brought into line with the passage *b*³, and therefore in the lowered position *40* of the tank and its pipe *C* liquid may flow outwardly from the pipe *B*² into the tank-pipe *C*, and the liquid will therefore be withdrawn from the burners, extinguishing the flame precisely as in the case of the ordinary construction heretofore employed; but said passage *d'* does not give outlet for the oil from the tank into the pipe *B*², because in lifting the pipe *C* the passage *d'* is raised above its point of coincidence with the passage *b*³ and has no further *45* communication with the interior of said pipe *B*².

Fig. 4 is merely a modification of the mechanics of the coupling *D*, showing a taper on the pipe *B*² in place of the collar and outer shoulder. To compensate for wear of the *55* tapered plug *B* and of the inner surface of the coupling *D*, the passage *b*² is made somewhat larger or elongated, so that it will be in communication with the passage *d'* after such wear of the parts.

60 I am acquainted with the construction set forth in the patent to Davis, No. 287,911, dated

November 6, 1883, in which the tank-pipe is rigidly connected with the horizontal oil-pipe, and the latter is mounted rotatably in the stove-frame for the purpose of tilting the also *65* rigidly-connected burner-pipes from a vertical to a horizontal position in lowering the tank, and in which the needle-valve in the burner-pipe is provided with a lever that strikes against a stationary projection of the frame in *70* the vibration of the burner-pipe, so as to close said needle-valve, and thus extinguish the burner and prevent escape of oil therefrom when the tank-pipe is lowered for the purpose of filling the tank. This is not my invention *75* or construction. In my construction the burner-pipes and the horizontal oil-pipe leading thereto are permanently fixed and non-rotatable and the tank-pipe alone is pivoted and movable. My valve, moreover, is located *80* in a stationary or non-rotatable part of the pipe, and the lever of said valve is arranged to project into the path of the pivoted tank-pipe.

I claim as my invention—

85 1. The combination, with a non-rotating horizontal oil-pipe of a vapor-stove leading to the burner or burners, and a tank-pipe pivoted to the non-rotating pipe and leading from an elevated oil-supply tank, of a valve arranged in one of said pipes and having its movable part provided with a projection or lever arranged in position to be engaged for the closing of the valve in the swinging movement of the tank-pipe, substantially as described.

90 2. The combination of an oil-pipe leading to a burner or burners, a pipe pivoted thereon leading from an oil-supply tank, and a valve for cutting off the flow of oil from the tank toward the burner, the oil-pipe and the tank-pipe being severally provided in their joint with passages which coincide to form a continuous passage for the backflow of oil from the oil-pipe to the tank-pipe when the latter *100* is depressed, substantially as described.

95 3. The combination, with the tank-pipe *C* and pipe *B*², having passages *b'*, *b*², and *b*³, of a coupling, *D*, rigid with the pipe *C*, but rotatably supported on the pipe *B*², and provided with *110* passages *d'* *d*², a valve for closing passage *b'*, and a lever connected with said valve arranged in the path of the pipe *C*, substantially as and for the purpose set forth.

In testimony that I claim the foregoing as my *115* invention I affix my signature in presence of two witnesses.

FREDERICK J. HUBBARD.
